Pennie, Davis, Moran & Edwards,
HIS ATTORNEYS.

UNITED STATES PATENT OFFICE

WILLIAM JACK, OF CLYDEBANK, SCOTLAND, ASSIGNOR OF NINE-TENTHS TO D. & J. TULLIS, LIMITED, OF CLYDEBANK, SCOTLAND, A CORPORATION OF GREAT BRITAIN

LAUNDRY PRESS

Application filed April 18, 1932, Serial No. 604,898, and in Great Britain March 16, 1931.

This invention relates to laundry presses of the type including a fixed lower buck, a movable upper buck which is lowered into operative position under the influence of a fluid pressure motor such as an air motor and is raised to inoperative position under the influence of a spring or springs.

In presses of this type it is desirable so to control the fluid pressure motor that both hands of the operator are employed simultaneously while the upper buck is being lowered under the influence of the pressure fluid motor. It is unimportant whether one or both hands is or are employed during the operation of raising the buck.

For ensuring that both hands will be employed while the upper buck is being lowered, various methods of operating the motor control valves have been proposed, one proposed arrangement including means whereby two handles are employed to maintain the supply of pressure fluid to the motor and one of such handles is employed for the purpose of exhausting the motor.

The present invention provides an improved valve control mechanism including a normally closed inlet valve, a normally open exhaust valve unitary with the inlet valve, a whipple tree pivotally connected at a point midway between its ends to said valves, and push buttons or the equivalent co-operating with the whipple tree and located one at each end thereof, the arrangement being such that, the valves can be displaced to open the inlet and to close the exhaust only when both push buttons or the equivalent are held in operative position simultaneously, which condition ensures that both hands of the operator will be employed simultaneously in actuating the push buttons or the equivalent while the upper buck is being lowered.

The whipple tree is operatively connected to the buck-operating mechanism by means including trip rods which serve to hold the valves in displaced or operative position independently of operation of the push buttons or the equivalent while the upper buck is in operative position.

To restore the valves to normal or inoperative position there is provided means includ-

ing a hand-operated or foot-operated lever operatively connected to the whipple tree and serving, when depressed, to restore the valves to inoperative position to permit return movement of the upper buck.

Desirably, the trip rods are arranged to act on the whipple tree through the medium of springs.

In the drawings Figs. 1-3 are, respectively, a vertical section, a front elevation, and a plan view, showing the improved valve control mechanism. Fig. 4 is a sectional organization view of a laundry press incorporating the improved valve control mechanism.

The valve control mechanism shown comprises a valve spindle 1 unitary with a normally closed pressure fluid inlet valve 2 and with a normally open exhaust valve 3, a whipple tree 4 pivotally connected midway between its ends to the valve spindle 1, and push buttons 5 co-operating with the whipple tree 4 and located one at each end thereof, the arrangement being such that, the valves can be displaced to open the inlet valves 2 and to close the exhaust valve 3 only when the push buttons 5 are held in operative position simultaneously, which condition ensures that both hands of the operator will be employed simultaneously in actuating the push buttons.

Acting on the valve 2 is a compression spring 2' which serves normally to maintain the valve 2, 3 in closed, and in open position, respectively.

The whipple tree 4 is pivotally connected at 6 to the bifurcated front end 7 of a cylindrical guide member 8 integral with the exhaust valve 3, and is so arranged that, if only one push button 5 is depressed, the whipple tree rocks idly on its pivot 6 without imparting movement to the valves 2, 3.

A pair of adjustable stops 9 mounted on the valve body 10, one at each end of the whipple tree 4, are engageable by the whipple tree 4 to limit the rocking movement thereof.

Operatively connecting the upper buck mechanism (Fig. 4) with the whipple tree 4 are trip rods 11 which serve to hold the valves 2, 3 in displaced or operative position independently of actuation of the push but-

tons 5 while the upper buck is in operative position.

The rods 11 act on the whipple tree 4 through the medium of compression springs 5 12 and each has a one-way operative connection at 23 with a lever 24 included in the operative train connecting the piston 25 to the upper buck 26.

To effect closure of the valve 2 and opening 10 of the valve 3 to permit return movement of the buck, a lever 13 which may be controlled by the foot of the operator is depressed, said lever being operatively connected to the whipple tree 4 through the medium of a link 14 15 and a bell-crank lever 15, 16 fulcrumed at 17, the arm 16 of the lever 15, 16 being bifurcated for engagement with the whipple tree 4. On depression of the lever translatory movement is imparted to the whipple tree in the direction to close the inlet and open 20 the exhaust.

Each push button 5 is carried on one arm 18 of a two-armed lever whose other arm 19 is engageable with one end of the whipple tree 4, both of said levers being fulcrumed on a common spindle 20.

21 denotes the pressure fluid supply shut-off valve.

22 denotes the press cylinder in which operates the piston 25.

I claim:

In a laundry press having a fixed buck and a platen movable into engagement therewith, 70 means for raising and lowering the platen by fluid pressure, a valve for admitting fluid under pressure to said means and a second valve for permitting the fluid to escape, means tending to close the inlet valve and open the 75 exhaust valve, a whipple tree connected to said valve at its pivot so that movement of the pivot will open the inlet valve and close the exhaust valve, a manually operated handle connected to each end of the whipple tree 80 whereby simultaneous operation of the handle is necessary to operate the valves, resilient means connecting the whipple tree with the platen and serving to hold the whipple tree in operative position when the platen is lowered, 85 said resilient means having provision for lost motion, and a foot operated means releasing said whipple tree against the pressure of the resilient means.

In testimony whereof I have signed my 90 name to this specification.

WILLIAM JACK.
